LIQUID FUEL BURNER

Rallston M. Sherman, Glastonbury, Conn., assignor to The Silent Glow Oil Burner Corporation, Hartford, Conn., a corporation of Connecticut

Application January 13, 1933, Serial No. 651,537

3 Claims. (Cl. 158—38)

This invention relates to liquid fuel burners and has for its object, among other things, the provision of means for controlling the flame in such burners, such means being embodied in a 5 relatively simple arrangement of parts adapted to be so controlled that a number of burner units supplied from the same source of liquid fuel supply may be brought to full flame and may be operated either simultaneously or at different times. This invention also contemplates improvements in the construction and operation 10 of the burner itself.

These and other objects of the invention will be best understood by reference to the following 15 description when taken in connection with the accompanying illustration of one specific embodiment thereof, while its scope will be more particularly pointed out in the appended claims.

In the drawings:—

20 Fig. 1 is a plan view in partial section of the base of a burner here employed to illustrate one embodiment of the invention, the parts above the base being broken away;

25 Fig. 2 is a central, longitudinal section of the burner shown in Fig. 1, taken on the line 2—2 in Fig. 1, showing the combustion tubes or shells and cover plate in place;

30 Fig. 3 is a vertical section on an enlarged scale of that portion of the burner coinciding with the point of liquid fuel delivery, such section showing the oil delivery conduit and pilot wick compartment;

35 Fig. 4 is a plan view on a reduced scale, partly broken away, showing two burner units with connections to the fuel supply receptacles; and

40 Fig. 5 is an elevation in partial section, also on a reduced scale, showing the fuel supply receptacles for the two burner units shown in Fig. 4 and their immediate connections.

45 Referring to the drawings and to the embodiment of the invention which is here submitted for illustrative purposes, as regards the feature of automatic lighting the invention has application to a wide variety of liquid fuel burners, but it is here shown as applied to a burner of the so-called combustion tube type comprising, as will be seen from Fig. 4, two separate burner units A and B mounted on the same support, each of which units is of substantially the construction 50 shown in Figs. 1 to 3 inclusive.

55 Referring first to Figs. 1 and 2, each unit comprises a cast iron base member 11, the bases of the two units being embodied in one casting connected by webs 13 (Fig. 4) and supported on the floor in any suitable manner, as by a rod or

pedestal connected to the central web. Each base (Figs. 1 and 2) comprises an outer, annular plate 15 and an inner, annular plate 17 connected one to the other by a series of webs 19 (Fig. 1), herein four in number, and providing 5 for annular air admission spaces 21 between the plates, the spaces being interrupted only by the webs 19. The inner plate is provided with a central air admission opening 23 surrounded by an up-turned ring-like flange 25, the outer edge of 10 said inner plate having also an up-turned ring-like flange 27 spaced from but concentric with the flange 25. The flanges 25 and 27 together with the bottom plate 17 form a relatively wide 15 annular trough 29 in the form of a channel, presenting a fuel space or chamber to which liquid fuel (herein referred to as oil for purposes of description) is admitted through an opening 31 in the bottom of the channel. The top of the space 20 defined by the channel is closed, except for the annular opening which permits direct escape of vaporized fuel to the combustion chamber, by a removable annular cover plate 33 seated on the 25 upper edge of the flange 25 and provided with a downwardly extending rim or sleeve 35 which fits within the flange and positions the cover plate 30 thereon. The walls of the cover plate extend outwardly over the channel 29, its outer peripheral edge portion being directed downwardly but spaced vertically from the bottom of the channel and peripherally from the inner walls of the flange 27 to provide the said annular exit 35 passage for the vaporized oil into the overhead combustion chamber. The edge of the cover plate is formed to provide a seat for a perforated sheet metal cylinder or shell 37 constituting one 40 of the combustion tubes of the burner. A similar but larger shell 39 is removably seated on the shouldered edge of the upright flange 27, the two shells forming between them a combustion 45 chamber 41. Preferably the outer edge 43 of the cover plate 33 extends slightly beyond the inner vertical limits of the combustion chamber so as to somewhat restrict the annular exit passage thereto of the oil vapor.

45 On the outer annular plate 15 there is also provided an annular fuel trough or channel 45 between the upright spaced, concentric flanges 47 and 49, and concentric, spaced, perforated, sheet metal cylinders 51 and 53 are removably 50 seated on the shouldered edges of such flanges to form between them a combustion chamber 55. The outer fuel channel 45 is connected with the inner, wider, fuel channel 29 by means of supply ducts 57 (Fig. 1) formed in the webs 19, 55

the oil supply opening 31 being positioned in the inner channel between two of such ducts. A removable cover plate 59 is provided with its outer periphery resting on the top of the sheet metal cylinders 37, 39 and 53, such cover plate closing the top of the intermediate, annular, air chamber 61 between the shells or tubes 39 and 53 and the top of the inner air space 63 within the inner tube 37. Such plate leaves an annular opening at the top of the outer combustion chamber 55 and is provided with a series of openings 65 registering with the inner combustion chamber 41 to provide for the escape of the products of combustion.

In the operation of a burner of this type, the burner is started by a preliminary heating operation, in the course of which the burner parts are raised to such a temperature that oil admitted to the base is vaporized through the heat generated by the burner, so that subsequently, in the normal or established operation of the burner, the oil vapor circulates through the channels and interconnecting passages and enters the combustion chambers where it commingles and is burned with the air admitted thereto.

In the burner operation, the oil is fed to the burner usually by gravity from some source, such as a constant level supply receptacle, providing for a definite running or normal feed level which can be accurately fixed and maintained. Such a level provides for the admission of oil to the bottom of the fuel channel in the base but limits the height to which liquid oil may rise in the base to some fixed point therein, such, for example, as is represented by the dotted line X—X in Fig. 3.

The preliminary heating of the burner may be accomplished by various means, but resort is commonly had to asbestos wicks permanently positioned in the fuel channels, these being first saturated by admitting oil to the burner base and then ignited manually by means of a lighted taper inserted from without through the tops of the combustion chambers. The oil supply is then checked until the wicks burn freely, after which the oil supply is increased until the burner develops its full heating capacity, when it burns through vaporization of the oil independently of the wick and may be regulated by controlling the rate of oil supply.

In the illustrated embodiment of the invention, an automatic lighting device is provided which comprises a constantly burning pilot light afforded by a pilot wick device, the latter supplied with liquid fuel from a level below the normal running feed level of the burner, so that it remains lighted during such period as the burner is out of operation. Such pilot light is so positioned that as soon as oil is supplied to the base at the normal operating level it will ignite the oil and create a pre-heating flame in each separate combustion chamber of the burner, but, on the interruption of the oil supply at its normal running level and extinguishment of the main flame in each combustion chamber, the pilot light will continue to burn.

Referring to Figs. 1, 2, and 3, where one form of the igniting device is illustrated as applied to each burner unit, the base is shown as supplied with the usual main or starting asbestos wicks 67 and 69 of annular form, the first of which is positioned in the outer part of the narrow channel 45 and the second in the outer part of the wide channel 29, the bottom of the wick 69 being cut away at the mouths of the ducts 57

to permit free flow of liquid fuel to the outer channel. In the normal operation of the burner, oil is admitted to the base through the supply opening 31 from the tubular conduit or pipe length 71 threaded into the bottom of the base 5 and depending vertically from the base, the bottom of the pipe being closed by the threaded cap 73 and a connection 75 for the main oil supply pipe being attached to the pipe 71 at a point preferably somewhat above the lower closed end 10 thereof. The depending pipe length provides a fuel compartment or well in which is positioned the elongated pilot wick 77 extending preferably well toward the bottom of the compartment and in any event below the pilot light level, which, 15 for illustration, may be represented by the line Y—Y (Fig. 3), which level is maintained by means later described.

The pilot wick 77 is in igniting relation to oil when entered into the channel, and for the purpose extends upwardly into the fuel channel 29, and herein into the annular space connecting such channel with the combustion chamber 41, being positioned closely adjacent the main wick 69, and herein pressed against the same by the edge 43 of the cover plate 33 so that its flame is adapted to ignite the oil conducted into the wick 69 by saturation or capillary attraction.

The covered portion of the wide channel 29 constitutes a vaporizing chamber which is subject to the heat transmitted to the thin sheet metal cover plate 33 from the inner air chamber and the highly heated walls of the combustion tubes 37. To direct the liquid fuel entering the base through the supply opening 31 inwardly into the vaporizing chamber and thence around the same and beneath the vaporizing cover plate 33, and before circulating through the inner and outer wick holding channels and the passages connecting the same, the bottom of the wide channel is provided with two arc-shaped, raised wall portions 19 (Fig. 1) intermediate the flanges 25 and 27, such wall portions extending part way around the channel to a point opposite the oil supply opening 31, whereat they are separated by a gap 81, the opposite ends of said wall portions terminating on opposite sides of the supply opening, whereat they are turned radially outward and connected to the flange 27 by the extensions 83. The extensions 83 lie between the opening 31 and the next adjacent ducts 57, so that any liquid fuel entering the channel, in being distributed to the various passages of the base, must first flow inwardly toward the inner wall 25 and thence around the same to the gap 81, thence around the outer wall 27 of the channel and through the ducts 57 to the outer groove 45.

Referring to Figs. 4 and 5, the main running oil supply for the two burner units is derived from the same constant level feeding device. While the latter may be of any desired type, herein for illustrative purposes it comprises the chamber or receptacle 85 to which oil is fed by gravity through the pipe 87 from a supply reservoir 89, which is replenished from time to time as may be necessary from any suitable source, such as the supply pipe 93 connected to a main supply tank (not shown). The chamber 85 is provided with a float 91 carrying a valve 93 which controls the supply orifice from the reservoir 89, the action of the float controlled valve establishing and maintaining in the receptacle 85, through gravitation of oil from the reservoir, a level conforming to the desired running level X—X at the burners A and B.

Oil is fed separately by gravity from the common constant level chamber 85 to the two burner units A and B through the supply pipes 95a and 95b, respectively, communicating with the bottom 5 of the chamber 85 and connected to the pipe extensions 97a and 97b, each of which connects with the depending compartment 71 of the corresponding burner unit through the pipe connection 75. A controlling valve 99a is provided 10 in the supply pipe 95a and a separate controlling valve 99b in the supply pipe 95b, so that the supply of oil at the feed level X—X may be established in respect to or withdrawn from both units simultaneously or independently each of the 15 other.

To maintain a constant and uninterrupted oil supply for both burner units at the lower pilot light oil level Y—Y, there are provided separate sources of supply for the two burner units comprising the constant level oil receptacles 101a 20 and 101b. These consist of small chambers fed from the supply pipes 95a and 95b, respectively, at a point in each case between the cut-off valve 99 and the higher level chamber 85, the supply 25 orifice in each small chamber 101 being controlled by a float-actuated valve which establishes and maintains in each receptacle a level conforming to the desired level Y—Y. The bottom of the chamber 101a opens directly into the supply pipe 30 97a and that of the chamber 101b directly into the supply pipe 97b, so that the closure of the valves 99a and 99b cannot interrupt the supply of oil to the pilot wick compartment at the level Y—Y.

With the described arrangement the pilot wick compartment in the depending pipe 71 of each burner remains constantly filled with oil supplied from the chamber (101a and 101b) up to the level Y—Y, and the pilot wicks for both burners 35 continue to be wet or saturated with oil so that after being initially lighted such wicks continue to burn indefinitely. When it is desired to start in operation either one of the burner units, as, for example, unit A, the control valve 95a is 40 opened admitting oil from the receptacle 85, the oil entering the base of the burner and rising to the level X—X, thereby wetting or saturating both main wicks. The admission of oil to the channels is followed immediately by the lighting of the 45 main wicks by the pilot wick, the flame traveling from the wick 69 through ducts 51 to the outer wick 67, the burner thereafter reaching its full, normal operation in the usual manner. If the 50 main oil supply is cut off by the valve 99a, the burner is cut out of operation but the pilot wick continues to burn. Since both units, though receiving their main running supply of oil from the same source of supply, receive their continuing pilot wick supply from separate constant 55 level sources, they may be started together or separately and each may be operated at full or partial capacity independently of the other.

While I have herein shown and described for the purposes of illustration one specific embodiment of the invention and one specific application thereof, it is to be understood that extensive changes may be made in the details, form, 5 relative arrangement of parts and connections, and that various applications of the invention may be made other than that to the specific form of burner herein shown, all without departing from the spirit of the invention. 10

I claim:

1. The combination with a plurality of liquid fuel burners, of high and low flame fuel feeding means comprising a first source of liquid fuel supply with means for maintaining it under a 15 constant head, said source communicating with each of said burners, connections for supplying each of said burners from a secondary source of liquid fuel supply maintained under a relatively 20 lower head, there being a separate secondary 25 source for each burner and the connections from each secondary source being independent of the connections from the other secondary source, and means intermediate said first source and each of said burners for controlling the delivery of 30 liquid fuel from said first source to the respective burners while leaving unimpaired the delivery of liquid fuel from said second source to said burners.

2. The combination with a plurality of liquid fuel burners, of high and low flame fuel feeding means comprising a first constant level fuel chamber communicating with a source of liquid fuel and with each of said burners, relatively 35 lower constant level secondary fuel chambers fed from said source of liquid fuel, one secondary chamber communicating with one of said burners and the other communicating separately with another of said burners, and means intermediate said first chamber and each of said burners 40 for controlling the delivery of liquid fuel from said first chamber to the respective burners while leaving unimpaired the delivery of liquid fuel from said second chambers to their respective burners. 45

3. The combination with a plurality of liquid fuel burners having each a pilot light device, of a common main supply source of liquid fuel for each of said burners, separate constant level fuel receptacles comprising each a supply source for 50 the pilot light device of one of said burners, fuel connections establishing communication between said common main source of supply and each of said pilot equipped burners and establishing separate communication between said separate constant level receptacles and their respective pilot devices, and means associated with the fuel connections between said source of supply and said burners for controlling the delivery of liquid fuel from said source to the respective burners. 55 60

RALLSTON M. SHERMAN.
